UNITED STATES PATENT OFFICE.

WALTER C. ROSS, OF NEW YORK, N. Y.

DESIGN FOR A COMBINATION PITCHER AND DRINKING GLASS.

Application filed February 27, 1928. Serial No. 25,609. Term of patent 7 years.

To all whom it may concern:

Be it known that I, WALTER C. Ross, a citizen of the United States, residing at New York city, county of New York, borough of Manhattan, and State of New York, have invented a new, original, and ornamental Design for Combination Pitcher and Drinking Glass, of which the following is a specification, reference being had to the accompanying drawing, forming a part thereof.

I claim:

The ornamental design for a combination pitcher and drinking glass, as shown.

WALTER C. ROSS.
